(57) **CLAIM**

The ornamental design for a bed roll, as shown and described.

DESCRIPTION

FIG. 1 is a top plan view of a bed roll showing my new design;

FIG. 2 is a bottom plan view thereof;

FIG. 3 is a top plan view of the bed roll shown in FIG. 1 in a partially open state;

FIG. 4 is a top plan view of the bed roll shown in FIG. 1, with the duvet detached;

FIG. 5 is a top plan view of the duvet portion, shown separately for completeness of illustration.

FIG. 6 is a top perspective view of the bed roll, shown without the duvet portion for completeness of illustration.

FIG. 7 is a side perspective view of the bed roll shown in FIG. 1, showing the duvet in a partially open state; and, FIG. 8 is another perspective view of the bed roll shown in FIG. 1, shown in a rolled-up state.
